CLAIM

The ornamental design for a valve module, substantially as shown and described.

DESCRIPTION

FIG 1 is a perspective view taken from the top, front and left side of a manifold valve unit showing my new design;

FIG. 2 is a front elevational view thereof;

FIG. 3 is a right side elevational view thereof;

FIG. 4 is a left elevational view thereof;

FIG. 5 is a top plan view thereof;

FIG. 6 is a bottom plan view thereof; and

FIG. 7 is a rear elevational view thereof.
